LICENSE TAG

Harry J. McKeon, Galesburg, Ill.

Application February 26, 1935, Serial No. 8,353

1 Claim. (Cl. 40—125)

This invention appertains to new and useful improvements in license tag holders and more particularly to a holder which can be used on license tags in various positions to accommodate various characteristics of the tag.

The principal object of the invention is to provide a holder which can be used either with tags having the slots therein for accommodating holders, or tags merely having the circular bolt openings.

During the course of the following specification and claim other important objects and advantages of the invention will become apparent to the reader.

15 In the drawing:

Figure 1 represents a front elevational view of the license tag held in place by the novel holder.

Figure 2 represents a sectional view taken substantially on line 2—2 of Figure 1.

20 Figure 3 represents a fragmentary vertical sectional view taken substantially on line 3—3 of Figure 1.

Figure 4 represents a fragmentary horizontal sectional view showing the holder being used with 25 a tag having a round opening.

Figure 5 represents a horizontal fragmentary sectional view showing the holder being used with a tag having a round opening, but without the retaining plate.

30 Figure 6 represents a perspective view of the retaining plate.

Figure 7 represents a perspective view of the retainer proper.

35 Figure 8 represents a fragmentary detail sectional view showing the holder employed without the retaining plate shown in Figure 6 and shown employed together in Figures 2 and 4.

Referring to the drawing wherein like numerals designate like parts, it can be seen that the holder 40 consists of the main plate 5 of rectangular shape and provided with a longitudinally extending rib 6 thereon through which and the main plate 5 is a threaded opening 7. Extending laterally from the ends of the main plate 5 and at right angles to the ends of the rib 6 and beyond the

side of the main plate 5 opposite from the side having the rib 6 are the lugs 8—8. These lugs 8—8 are intended to engage through the slot 9 of a license tag 10 so equipped, Figure 2 showing the usual bracket 11 having the slot 12 therein coincident with the slot 9.

In conjunction with the main plate 5, a retaining plate 13 is employed, the same having notches 14 at the ends thereof and a central opening 15 through which the bolt 16 extends. When the tag 10a (see Figure 4) is provided merely with a circular opening 17, the retaining plate 13 can be employed as a washer between the head of the screw and the tag 10a, or as shown in Figure 5, the retaining plate can be entirely eliminated, but in both events the rib 6 anchors the main plate 5 by engaging into the slot 12 of the bracket. When the tag 10 is provided with the slot also, the lugs 8 engage through the slot 9 (see Figure 2) and into the notches 14—14 of the retaining plate 13, which plate in this instance serves as a washer between the head of the screw 16 and the front side of the tag.

While the foregoing specification sets forth the invention in specific terms, it is to be understood that numerous changes in the shape, size and materials may be resorted to without departing from the spirit and scope of the invention as claimed hereinafter.

Having described the invention, what I claim as new is:

In combination with a license tag having an opening therein, a slotted supporting bracket for the tag, a holder, said holder including a main plate, a rib extending across the plate, said rib being engageable into the slot of the bracket, said plate and rib having a threaded opening therethrough, lugs extending laterally from the ends of the plate in a direction beyond the opposite side of the plate from the side having the rib, and a screw for disposition through the tag, bracket and threaded opening of the said plate and rib.

HARRY J. McKEON.
